UNITED STATES PATENT OFFICE.

JOHANN G. PETERSON, OF HARTFORD, CONNECTICUT.

ELECTRIC SWITCH.

1,090,313.

Specification of Letters Patent.

Patented June 9, 1914.

Application filed October 2, 1911. Serial No. 652,235.

To all whom it may concern:

Be it known that I, JOHANN G. PETERSON, a citizen of the United States, residing at Hartford, in the county of Hartford and 5 State of Connecticut, have invented certain new and useful improvements in Electric Switches, of which the following is a specification.

This invention relates to electric switches, 10 and although I do not intend to restrict myself to the incorporation of said invention in any particular type of said device, the same is highly advantageous when embodied in what is known as a "push switch." An article of the latter type involves a rocker and one or more operating levers connected therewith, it being the primary purpose of 15 the present invention to provide means of a simple and inexpensive character by which such a lever or levers can be readily united with the rocker and without the necessity of a rivet, rivets or equivalent means, the organization being such that the connection between the lever or levers can be made quite 20 close to the axis of oscillation of said rocker.

In the drawings accompanying and forming part of the present specification I have illustrated in detail one of the several embodiments of the invention which to enable 25 those skilled in the art to practice the same will be fully set forth in the following description, while the novelty of said invention will be included in the claim following said description. From this statement it will be 30 evident that I do not restrict myself to said showing; I may depart therefrom in several respects within the scope of my invention covered in said claim.

Referring to said drawings: Figure 1 is a 35 front elevation of a push switch including my invention. Fig. 2 is a side elevation of said switch. Fig. 3 is a bottom plan view of the same. Fig. 4 is a detail view of a lever with the composition button in section. Fig. 5 is a sectional elevation of said lever, the section being at right angles to that of Fig. 4, and, Fig. 6 is a side elevation of said rocker.

Like characters refer to like parts 40 throughout the several figures.

In Fig. 1 I have shown a push switch comprising a rocker 10 and a pair of duplicate levers 11 and 12. The rocker 10 except as to its manner of connection with the two operating levers 11 and 12 is of the ordinary construction, and for this reason need not be

specifically described. Said rocker like the two levers 11 and 12 is generally made of sheet metal, it being the custom to provide the levers with composition buttons each denoted by 13 and into which the respective levers are molded and anchored. While I have shown two levers connected with the rocker, this is not essential, the invention not concerning the number of levers but 50 rather the connection between one or more of said levers and the coöperating rocker, and I might say at this point that the said connection is of such a nature that it can be arranged closer to the center of motion of the 55 rocker than has heretofore been possible in view of which compactness has been attained.

As will be gathered from the observations already made the invention resides in a connection between a rocker and a lever, of which the parts shown in the drawings are fair types, and in the present instance one of said elements has an arm, the other having a slot through which said arm is passed 60 when the two parts are in a certain relation, said arm having a transverse head adapted to overlie the solid part of the slotted member when the lever and rocker are in working positions, so that the lever cannot be 65 accidentally displaced. In the present instance this arm is on the rocker, while the lever has a slot through which the arm is passed, although as intimated this construction is not essential, although it is advantageous. While in like manner I do not limit myself to the formation of the slot in any particular way, I have illustrated a slot of 70 a shape which has particular utility as will 75 hereinafter appear.

The rocker 10 at opposite sides thereof has arms 14 and 15 which are generally integral with the body of the rocker and which can be struck up therefrom. Each arm has an intermediate reduced portion 16, by reason of which there are formed on the said arm two transversely aligned bearing shoulders or supports 17, and a transverse or T-head 18, the levers 11 and 12 as will hereinafter appear when in assembled relation 80 encircling and relatively turning upon these reduced portions at which time they rest against the bearing shoulders or supports 17 and are held against displacement by the T-heads 18 as shown in Figs. 1 and 3. Each 85 of the levers 11 and 12 has near the inner terminal or tail portion an elongated trans-

verse slot, the length of the slots slightly exceeding the length of the respective T-heads 18, by virtue of which the levers can be mounted in place by passing said T-heads 5 through said slots. Each of said slots, as will be evident, consists of a straight portion 19 and a circular portion 20, and the wall of each of said circular portions as will hereinafter appear encircles a co-operating 10 reduced portion 16 to thereby provide for a pivotal joint.

I will describe the mode of connecting one of the levers (such as 11) with the rocker 10, this description of course applying to the other lever. The slot in the lever 11 is brought into register with the transverse or T-head 18 (see Fig. 2) so that said lever can be slipped over the arm 14 until the wall of the slot is in line with the reduced portion 16. Said lever will then be moved slightly laterally so as to cause the wall of the circular portion 20 of the slot to inclose said reduced portion 16 at which point the said lever will be swung around 25 to approximately right angles to its original position as indicated in Fig. 1 so as to thereby bring the T-head 18 across the solid portion of said lever and hence prevent the same being accidentally displaced. Owing to the 30 fact that the portion 20 of the slot is round or circular, the rocker 10 and lever can freely relatively rock, so that for this reason such a construction is advantageous, although not essential. To disconnect the lever 35 it will be swung around from the position shown in Fig. 1 to that illustrated in

Fig. 2 and the said lever 11 will then be manipulated until its slot is in direct register with the T-head 18 at which point said lever can be easily slipped from place.

What I claim is:

A switch comprising a rocker and a lever, the lever having an elongated slot, one portion of which is circular and another portion of which is straight, said rocker 40 having an arm reduced between its ends to provide two bearing shoulders and a T-head, the entire length of said slot being greater than the length of said T-head and the diameter of the circular portion of said 45 slot being slightly greater than the width of said reduced portion, said head being insertible through said slot when the arm and lever are out of normal operative relation, so that the lever can be passed over said 50 head until its slot registers with the reduced portion of said arm, whereby said lever can be turned through an angle of approximately ninety degrees to bring it into normal operative relation, the wall of the 55 circular portion of said slot engaging the reduced portion of said arm to pivotally connect the arm and lever and said head and bearing shoulders engaging opposite faces of the lever to prevent accidental displacement of the lever.

In testimony whereof I affix my sig
in presence of two witnesses.

JOHANN G. PETERSON
